SAFETY RAZOR

Filed Nov. 17, 1930

Inventor
Ralph E. Thompson
By his Attorney, J. M. Kenway.

UNITED STATES PATENT OFFICE

RALPH E. THOMPSON, OF BROOKLINE, MASSACHUSETTS, ASSIGNOR TO GILLETTE SAFETY RAZOR COMPANY, OF BOSTON, MASSACHUSETTS, A CORPORATION OF DELAWARE

SAFETY RAZOR

Application filed November 17, 1930. Serial No. 496,165.

This invention relates to safety razors, and has as its general object to improve the facilities for adjusting the degree of exposure of the cutting edges of safety razors employing transversely flexible blades.

In the ordinary safety razor the blade edges are positioned exactly by being clamped between the cap and guard members of the holder, no variations of the amount of exposure of the edges of the clamped blade being available to the user. It is desirable to have available on a safety razor means for adjusting the amount of exposure of a blade edge for two reasons:

15 First. The edge exposure defined by the position of the blade between the cap and guard members of a holder is not always correct, due to varying dimensions of the various elements of a razor, which may be in 20 turn due to manufacturing inequalities. For example, it is difficult to manufacture a large number of blades having exactly the same width, and it is almost impossible to manufacture a large number of cap and guard 25 members which will be exact duplicates of the desired standard.

Second. All shavers do not desire safety razors having the same degree of edge exposure. This may be due to different skin 30 conditions or due to the particular shaving habits of an individual.

According to this invention, improved means are provided for adjusting the amount of exposure of each shaving edge of a safety 35 razor employing transversely flexible blades. This is accomplished by having adjusting screws mounted in either the cap or guard member which may be adjusted to hold the cap and guard separated an amount depending upon the adjustment desired.

The invention will now be explained with reference to an illustrative embodiment thereof shown in the accompanying drawings, of which:

45 Fig. 1 is an elevation view looking down along the handle of an assembled safety razor;

Fig. 2 is a side sectional view of the safety 50 razor shown by Fig. 1, taken along the lines 2-2 of Fig. 1;

Fig. 3 is an end sectional view taken along the lines 3-3 of Fig. 1;

Fig. 4 is a partial end view of a razor showing extreme adjustment of the adjusting screws, and

Fig. 5 is a plan view of a safety razor blade, according to this invention.

Referring now to the drawings, the blade 6, shown by Fig. 5, is provided with the ordinary positioning openings 7 through which the positioning studs on the cap member extend, the central opening 8 through which the threaded stud of the cap member extends, and the four smaller openings 9 for the accommodation of the adjusting screws 11.

As shown by Figs. 1, 2, 3, and 4, the guard member 10 is provided with the four adjusting screws 11 which are adapted to pass with clearance through the holes 9 in the blade. These adjusting screws serve to hold the cap member 12 and the guard member 10 apart the desired distance, as determined by the degree of adjustment of the screws 11. When the screws are withdrawn, so that they exert no pressure on the cap member 12, the edges of the blade 6 have their lowest exposure and give the closest shave. When all of the screws 11 are screwed in, to separate the cap member 12 from the guard member 10, an increased edge exposure of 80 the blade is obtained, which results in a closer shave, this degree of exposure depending, of course, upon the amount the adjusting screws have been screwed into the cap member.

Fig. 4 illustrates the extreme position of 85 the adjusting screws, showing how the cap member can be held so far away from the guard member that the blade is not even flexed when clamped. This corresponds to the position of maximum edge exposure.

It is not necessary, of course, that all of the adjusting screws have their position changed at a given time. For example, only the adjusting screws at one end of the guard may be adjusted to change the edge exposure 95 on both sides at one end of the blade. Likewise, the two adjusting screws along one longitudinal side of the guard may be adjusted to vary the edge exposure along each edge of the blade. It may be desirable to 100

have one end of the blade have more edge exposure than the other, when shaving next to the ears, for example. This invention provides means for changing the edge exposure of a blade to correct for manufacturing inequalities, and to exactly suit the individual requirements of the shaver.

Whereas one or more embodiments of this invention have been described for the purpose of illustration, it should be understood that this invention is not limited to the exact details described, as many departures may be made by those skilled in the art without departing from the spirit of the invention.

15 It will be noted that the ends of the adjusting screws 11 are reduced and pass through the openings 9 in the blade with appreciable clearance. The clamping and flexing action of the cap and guard upon the blade is, therefore, not interfered with and the blade is accurately positioned and shaped by these members when the handle of the razor is tightened to draw them together. Moreover a rigid connection is established in 20 all positions of adjustment and there is no tendency in the razor to back off or twist in use with respect to the handle.

What is claimed is:

1. A safety razor comprising, in combination, a perforated blade adapted to be transversely flexed when clamped in shaving position, cap and guard members for clamping said blade, and an adjustable extension on each end of one of said members for spacing said members a desired distance apart, said extensions being shaped to pass freely through the perforations of the blade without interfering with the flexing thereof.

2. A safety razor comprising, in combination, a perforated blade adapted to be transversely flexed when clamped in shaving position, cap and guard members for clamping said blade, and an adjustable extension on said guard member for spacing said guard member and said cap member a desired distance apart, said extension passing through the perforation of the blade and leaving the latter free to be flexed by the cap and guard members.

3. A safety razor comprising, in combination, a blade adapted to be transversely flexed when clamped in shaving position, cap and guard members for clamping said blade, and an adjustable extension on each end of said guard member for spacing said guard member a desired distance from said cap member, said blade having clearance openings registering with said extension.

4. A safety razor comprising, in combination, a blade adapted to be transversely flexed when clamped in shaving position, cap and guard members for clamping said blade, and a member threaded into one of said members and contacting with the other of said members for spacing said members a desired dis-

tance apart, said blade having clearance openings for the passage of said threaded member.

5. A safety razor comprising, in combination, a blade adapted to be transversely flexed when clamped in shaving position, cap and guard members for clamping said blade, and an adjustable member threaded into said guard member and contacting with said cap member for spacing said members a desired distance apart, said blade having a clearance opening for the passage of said threaded member.

Signed at Boston, Massachusetts, this 14th day of November, 1930.

RALPH E. THOMPSON.
